UNITED STATES PATENT OFFICE.

ORIN J. MILLER, OF HURDSFIELD, NORTH DAKOTA.

GRAIN-DOOR.

1,153,509.

Specification of Letters Patent.

Patented Sept. 14, 1915.

Application filed January 20, 1914. Serial No. 813,236.

To all whom it may concern:

Be it known that I, ORIN J. MILLER, a citizen of the United States, residing at Hurdfield, in the county of Wells and 5 State of North Dakota, have invented a new and useful Grain-Door, of which the following is a specification.

The invention relates to improvements in grain doors.

10 The object of the present invention is to improve the construction of grain doors, and to provide a simple inexpensive grain door of strong and durable construction, designed for use on box cars and adapted to 15 be employed for hauling grain and various other kinds of material in bulk, and capable of providing a tight connection and of preventing leakage of the contents of the car.

20 A further object of the invention is to provide a grain door having separate sections designed to be used conjointly or independently and adapted to be raised one at a time by hand without the use of operating mechanism and secured out of the 25 way at the top of the car.

With these and other objects in view, the invention consists in the construction and 30 novel combination of parts hereinafter fully described, illustrated in the accompanying drawings, and pointed out in the claims hereto appended; it being understood that various changes in the form, proportion, size and minor details of construction, with- 35 in the scope of the claims, may be resorted to without departing from the spirit or sacrificing any of the advantages of the invention.

In the drawings: Figure 1 is an elevation 40 of the inner face of a grain door, constructed in accordance with this invention, and shown applied to a car, the latter being in section. Fig. 2 is a perspective view of the same, the door sections being folded against the top of the car. Fig. 3 is a transverse 45 sectional view. Fig. 4 is a horizontal sectional view on the line 4—4 of Fig. 1. Fig. 5 is a detail sectional view, illustrating the manner of supporting the hinged edges of 50 the sections at the top of the car. Fig. 6 is a detail perspective view of the upper portion of one of the guides. Fig. 7 is a detail perspective view of one end of the connecting and pintle rod of the upper door 55 section. Fig. 8 is a detail view of one end of the connecting and pintle rod of the

lower door section. Fig. 9 is a detail view of the sliding auxiliary door.

Like numerals of reference designate 60 corresponding parts in all the figures of the drawings.

In the accompanying drawings in which is illustrated the preferred embodiment of the invention, the grain car door, which may be constructed of any suitable material, either wood or metal, or a combination of both, is composed of separate interlocked upper and lower sections 1 and 2, provided at their upper edges with horizontal pintle and connecting rods 3 and 4, extending 65 through alined eyes 5 and 6 of metallic cleats 7 and 8. The upper door section 1 is adapted to rest upon the upper edge of the lower section 2, and it is provided at its lower edge with a metallic strip 9, secured to the inner face of the upper door section 1 and projecting below the lower edge thereof and overlapping the joint formed by the upper and lower sections to provide a tight joint or connection to prevent 70 leakage of the grain or other material at that point. The metallic strip 9 also extends between the horizontal rod 4 and the lower door section to interlock the adjacent edges of the door sections to prevent 75 the upper door from swinging inwardly. The cleats 7 of the upper door section 1 are located at the center and ends of the said door section, and the cleats 8 of the lower door section are located at the ends of such 80 section and at points at opposite sides of the center of the same to provide an intervening space for an auxiliary door opening 85 10, but any other desired number of cleats 90 may be employed for bracing and reinforcing the upper and lower door sections. The intermediate cleats of the lower door section are provided with depending lugs or extensions 11 engaging sockets 12 in the sill or floor of the car and interlocking the bottom portion of the lower section with the car, whereby the lower section is held 95 against inward movement.

The ends of the horizontal connecting and pintle rods 3 and 4 are extended and bent 105 into hooks 13 and 14, which engage around vertical guides 15, located at opposite sides of the door opening 16 of the car and suitably secured to the door casing and spaced from the door opening to form ways, and 110 permit the upper and lower sections of the grain door to fit against the same and be-

tween the said guides, as clearly illustrated in Fig. 4 of the drawings. The guides, which are constructed of suitable metal, preferably consist of bars approximately U-shaped in cross section composed of inner and outer flanges and a straight connecting portion, the outer flanges being suitably secured to the sides of the car. The inner flanges are arranged in spaced relation with 10 the side of the car to form ways and the hooks which engage around the inner flanges extend into the ways and are slidable along the guide bars. The hooks are interlocked with the vertical guides and enable the door sections to slide upwardly and downwardly 15 thereon, and the rods also form pintles for enabling the door sections to swing upwardly and downwardly to carry the door sections to a folded position beneath the top 20 of the car, as illustrated in Fig. 2 of the drawings, and to return them to a vertical operative position. The opposite guides are provided with extended upper extensions 17 having inclined lower portions and vertical 25 upper portions, which are offset from the plane of the body portions of the guides by the said inclined portions of the extensions, as clearly illustrated in Fig. 6 of the drawings. The extensions 17 are also provided 30 with top portions 18, having vertically disposed attaching terminals 19 and forming seats for the terminal portions of the horizontal rod 3 of the upper door section. The attaching terminals 19 are suitably secured 35 to the interior of the car near the top of the door opening 16, and when the upper door section is moved upwardly on the guides when it is desired to arrange it out of the way, the terminals of the rod 3 are moved 40 over and are arranged upon seats 18. The upper section is then swung upwardly and inwardly against the top of the car and is secured in such position by a pivoted gravity catch 20, consisting of a hook having a lower 45 engaging portion or bill, arranged to extend beneath and engage the free edge of the upper door section, as clearly illustrated in Fig. 2 of the drawings.

The hooks 14 of the horizontal connecting 50 and pintle rod 4 are set at an inclination and extend upwardly and outwardly with respect to the lower door section 2, and they are provided with depending engaging portions or lugs 21, set approximately at an 55 acute angle to the plane of the hooks 14 and adapted when the lower door section 2 is moved to the upper ends of the guides 15 and is swung inwardly and upwardly against the upper door section to be carried 60 inwardly and caused to project through vertical slots 22 in the extensions 17 of the guides 15, whereby the upper or outer edge of the lower section is supported in an elevated position. The lugs 21 are arranged 65 normally in substantially a vertical position

so as to slide in the guide ways when the lower door section is in a vertical position. The horizontal rod 3 of the upper door section is loose in the eyes 5 of the cleats 7, and the upper door section is adapted to turn on 70 the rod while the horizontal rod 4 of the lower section is rigidly secured in the eyes of the cleats 8 and rotates with the lower door section to cause a positive oscillatory movement of the lugs or engaging portions 75 21 to carry the latter into and out of the slots 22 of the vertical guides. The lugs or engaging portions 21 are slightly curved and present rounded or convex faces to the bottom walls of the slots to facilitate an easy 80 swinging movement of the lower door section.

The lower door section 2 is held in an elevated position at the top of the car by a supporting device 23, constructed preferably 85 of rod metal and consisting of a central pivot portion 24, downwardly diverging inclined sides 25 and upwardly extending terminal arms or portions 26, arranged at an angle to the lower portions of the sides 25 90 and forming crotches or seats to receive the depending lugs 11 of the lower door section. The central pivot portion 24 is mounted in a suitable bearing opening at the top of the car and the sides of the support are adapted 95 to be readily swung into and out of engagement with the lugs 11 and they are spaced apart to permit an independent operation of the gravity catch 20. The door by being constructed of two sections is easy for one 100 man to handle even when constructed sufficiently heavy to withstand the strains incident to the use of grain doors, and it is unnecessary to provide hoisting mechanism for raising and lowering the grain door. The 105 door sections swing inwardly and when in their closed position fit against the door casting at the interior thereof and provide a tight closure. Also either one or both of the door sections may be used and when not 110 in use, they are securely held in an elevated position out of the way.

The lower door section is provided on its exterior at opposite sides of the auxiliary door opening with vertical guides 27 receiving an auxiliary door 28 preferably constructed of metal and adapted when open to relieve the interior pressure in the usual manner. The auxiliary door is provided at its upper edge with aligned eyes 29, in which is arranged a transverse pintle portion 30 of an approximately U-shaped link having spaced sides 31, which are connected with an operating lever 32. The operating lever 32 consists of a central handle portion or arm 33, laterally extending pivot portions 34 and spaced side arms 35 having terminal pivots 36, which extend into eyes 37 of the sides of the U-shaped link. The operating lever is mounted on the lower sec- 115 120 125 130 135

tion of the door above the auxiliary door in suitable bearings 38, and it is adapted to be oscillated to raise and lower the auxiliary door. In the accompanying drawings, the 5 operating lever is shown constructed of a single piece of rod metal bent and twisted to form the operating handle, which is provided with a terminal loop 39 to enable it to be easily grasped and operated. When 10 the auxiliary door is closed, the lever and the link are located in the space between the sides of the door casing and do not interfere with the opening and closing of the ordinary car door (not shown).

15 What is claimed is:—

1. The combination with a car having a door opening, and guide bars located at opposite sides of the door opening and arranged in spaced relation with the side of 20 the car to form ways, said guide bars being provided at their upper portions with slots or openings, of a door provided at opposite sides with hooks engaging around the guide bars and extending into the said ways, said 25 hooks being provided with lugs normally arranged in a substantially vertical position so as to slide in the ways and adapted to be carried through the slots or openings of the guide bars when the door is swung up- 30 wardly.

2. The combination with a car having a door opening, and guide bars located at opposite sides of the door opening and arranged in spaced relation with the side of 35 the car to form ways, said guide bars being provided at their upper portions with slots or openings, of a door provided at opposite sides with hooks engaging around the guide bars and extending into the said ways, said 40 hooks being provided with projecting lugs normally arranged in a substantially vertical position so as to slide in the guide ways and be carried through the slots or openings when the door is swung upwardly, said lugs 45 being curved and presenting rounded convex faces to the lower end walls of the said slots or openings.

3. The combination with a car having a door opening, of guide bars located at opposite sides of the door opening, said guide 50 bars being provided with upper seats and having slots located below the same, a door composed of upper and lower separable sections, upper and lower pintle rods extending entirely across the door opening and having 55 terminal means for slidably engaging the guide bars, eyes carried by the upper section of the door and receiving the upper pintle rod which is movable upwardly along the guide bars to the said seats, the other 60 pintle rod being provided with rigid means for engaging the slots of the guide bars, and means for rigidly connecting the lower door section with the lower pintle rod, whereby 65 the lower door section is adapted, in swinging, to carry the rigid projecting means into and out of the said slots.

4. The combination with a car having a door opening, of guide bars located at opposite sides of the door opening, said guide 70 bars being provided with upper seats and having slots located below the same, a door composed of upper and lower separable sections, pintle rods extending entirely across the door opening and having terminal hooks 75 engaging around the guide bars, eyes carried by the upper section of the door and receiving one of the pintle rods, the hooks of such pintle rods being adapted to engage with the seats of the guide bars, and means 80 for rigidly connecting the lower door section with the other pintle rod, the hooks of the latter being provided with means arranged to be carried by the swinging movement of the lower door section into and out 85 of the slots of the guide bars.

In testimony, that I claim the foregoing as my own, I have hereto affixed my signature in the presence of two witnesses.
